UNITED STATES PATENT OFFICE

LOREN WARD EMLER, OF ASTORIA, OREGON

WEATHER STRIP FOR SWINGING CLOSURES

Application filed August 20, 1929. Serial No. 387,120.

This invention relates to weatherstrip and is particularly adaptable to swinging closures such as doors, shutters, or the like, and an object of the invention is to provide a weatherstrip that will prevent draft between the lower edge of the door and the sill.

Another object of the invention is to provide a weatherstrip that is seatable in the sill so that occupants of the dwelling will not stumble over the weatherstrip when applied in operative position.

Further objects of the invention are to provide, in the manner as hereinafter set forth, a weatherstrip of the character referred to, which is strong, compact and durable, thoroughly reliable for its intended purpose, very simple in its method of assembly, that will not detract from the appearance of the dwelling, and is comparatively inexpensive to manufacture and install.

With the foregoing and other objects in view, the invention consists of a novel construction, combination and arrangement of parts as will be hereinafter more specifically described and illustrated in the accompanying drawings, wherein is disclosed an embodiment of the invention, but it is to be understood that changes, variations and modifications may be resorted to without departing from the spirit of the claim hereto appended.

In the drawings, wherein like reference characters denote corresponding parts throughout the several views:

Figure 1 is a fragmentary vertical section in detail through a closure frame with the closure in the open position, and illustrating an application of the present invention therewith.

Figure 2 is the same view as Figure 1 with the closure in closed position, and illustrating the present invention in operative position.

Figure 3 is a horizontal section taken substantially on line 3—3 of Figure 1, and,

Figure 4 is a perspective view of the movable strip.

Figure 5 is a perspective view of the rigid plate.

Referring to the drawings, wherein is disclosed an embodiment of the invention, 6 in-

dicates generally a frame for swinging closures such as doors, windows or the like having a sill 7 at its lower end that is adapted to form the lower portion of the frame.

It is to be understood that the frame 6 is to be inserted in either a window or door opening in a building in any conventional manner. On each side of the frame there is formed the conventional jamb 8 against which abuts the inner marginal edges of the sides of a door or window or shutter 9. The closure 9 may be of any conventional type and is hingedly connected to the frame 6 in any suitable manner so as to swing outwardly in the open position from that shown in Figure 2 of the drawings.

The invention is illustrated as being applied to a door, but it is to be understood that the invention could be applied directly to the sill 7, in event the same was used in connection with any swinging closure such as a shutter, window, or the like.

In illustrating the invention as applied to a door, it is customary in the building trade to apply a threshold strip 10 of wood across the upper face of the sill 7. The strip 10 is of a width materially greater than the thickness of the door so that it will extend rearwardly of the forward edge of the jamb. The inner portion of the lower edge of the door 9 is formed with a notch having a vertical inner wall 11 and an upwardly inclining wall 12 merging at its inner end with the vertical wall 11. The wall 12 extends from the inner face of the door substantially half way through the door before it meets the vertical wall 11.

A strip of rubber or other resilient material may be secured to the face of the inclined wall 12 to provide cushion means for the weatherstrip to be presently described. The resilient strip of material is indicated at 13. The door groove is co-extensive with the width thereof.

The base plate indicated generally at 14 is of elongated rectangular configuration having a flat longitudinal margin 15 provided with spaced openings 16 through which holdfast means extend for securing the plate to the threshold 10. The opposite longitudinal

edge of the plate 14 is formed with an upstanding lip 17 and intermediate the lip 17 and the marginal portion 15 the plate is provided with a depression 18 co-extensive with the length thereof.

5 The threshold strip 10 is provided with a cavity 19 to receive the depressed portion 18 of the plate 14. The length of the plate 14 is to be as desired so that it will extend between the sides of the frame 6 and in abutment with the upper face of the threshold strip 10. The plate 14 may be formed of light gauge metal consistent with its use and preferably brass or other non-corroding metal.

10 15 An elongated flat strip of metal of suitable thickness 20 is formed with an arcuate fold 21 coextensive with the rear edge thereof which is adapted to overlap the upstanding lip 17 on the plate 14. The width of the plate 20 is such as it will seat in the depression 18 when the door is opened.

20 25 Adjacent one end of the plate 20 there is rigidly secured thereto an upstanding resilient arm 22 of arcuate configuration. The lower end of the jamb 8 has an arcuate recess 23 cut therein of the same configuration as the flexible arm 22 so that when the door abuts against the arm 22 in closed position, the recess 23 is sufficient to seat the arm therein without causing pressure upon the door.

30 35 It is within the contemplation of this invention to provide a pair of arms 22 at each end of the movable strip 20 and in the latter event, it will be necessary to provide a pair of grooves at the lower outer edge of each of the jambs 8.

40 45 In the application of the invention, the threshold strip 10 is first provided with the recess 18 and the plate 14 is secured by hold-fast means such as screws 24 to the upper face thereof with the depression 18 countersunk in the depression 19. The inner edge of the depression 19 is to be formed with clearance so that the folded edge 21 will not bind thereon and prevent the operation of the weather-strip in accordance with the present invention.

50 55 The strip 20 is then applied or placed in the depression 18 with the lap 21 overhanging the upstanding edge 17 and in this position, the arm 22 will be in outstanding spaced relation to the recess 23 in the jamb. When the door 9 or other closure is closed, the arm 22 abuts the inner face of the door and is forced in the recess 23. The rocking movement of the arm 22 causes the strip 20 to seat itself in the notch on the lower edge of the door thereby forming a baffle to prevent draft from coming in between the crack between the threshold strip 10 and the lower edge of the door.

60 65 When the door is opened, the plate 20 falls by its own weight and the arm 22 assumes the position shown in Figure 1 of the drawings.

70 It is to be understood that by describing in detail herein, any particular form, structure or arrangement, it is not intended to limit the invention beyond the terms of the several claims or the requirements of the prior art.

Having thus described my invention, what I claim is:

75 A weatherstrip for swinging closures comprising a pair of loosely hinged members consisting of substantially flat longitudinally disposed baffle and base plates respectively, the said base plate having a depression coextensive with its length for seating the said baffle plate therein substantially flush with the upper surface of the base plate, an upstanding lip adjacent one longitudinal edge of the depression and a relatively broad flat marginal portion adjacent the opposite longitudinal edge provided with spaced openings for receiving fastening means for attaching the base plate to a threshold, and the said baffle plate having an arcuate fold coextensive with one edge thereof and overlapping the said upstanding lip of the base plate to provide a hinge joint, and having upon its upper face an upstanding resilient door actuated lifting arm of arcuate formation.

80 85 In testimony whereof I affix my signature.
LOREN WARD EMLER.
